HYDRAULIC PUMP STRUCTURE

George E. Dean, Walker Township, Kent County,
and Charles G. Willett, Grand Rapids, Mich.;
said Dean assignor to said Willett

Application September 28, 1931
Serial No. 565,474

1 Claim. (Cl. 103—38)

This invention relates generally to a hydraulic pump structure and more particularly to a lever arrangement with an adjustable fulcrum for operating the same whereby the amount of travel of the operating lever may be controlled.

The structure herein described is primarily adapted to be used with the hydraulic operating mechanism for a dump body on a truck but it is to be understood that the mechanism may be used wherever needed.

During the elevation of a loaded dump truck body the resistance thereof gradually decreases as the body is tilted and consequently the amount of leverage can be and should be decreased in order to facilitate or speed up the dumping operation. In other words, less power is needed to oscillate the manual operating lever when the load is partly elevated and consequently the fulcrum of the lever can be changed to cause the dumping mechanism to speed up its operation.

In the above manipulation it will be noted that the resistance of the load to dumping position progressively decreases and hence the shift of the fulcrum to give less advantage does not need to be made with any degree of speed because the operator can easily shift the fulcrum changing mechanism back to the higher degree of power application should the movement of the load be stopped with the result that a considerable amount of power would be needed to again put it in motion.

It will be appreciated, however, that our invention might be readily used in a situation where it was necessary to change from a low leverage to a high leverage and in such case it is necessary that the change be rapidly made in order that the weight of the body or load which is being moved be kept in motion in order that the inertia of the same does not have to be overcome in a starting operation. That is, the leverage system is changed to a higher degree of leverage and the same cannot be shifted in any manner to increase this advantage, as could be done in the previous case, and, consequently, it is necessary that the shifting be rapidly done and we provide spring means for accomplishing this result.

Briefly described, our invention consists of a lever of the first class having an adjustable fulcrum therefor, this fulcrum being controlled by an auxiliary lever mounted upon the main lever whereby the advantage of the leverage arrangement may be changed. Spring means are provided for facilitating the leverage change from a long leverage to a short leverage.

The further objects and advantages will be

obvious to one skilled in the art from the following description.

In the drawing:—

Fig. 1 is a side elevation of our improved lever mechanism as applied to a pump.

Fig. 2 is a side view of the mechanism shown in Fig. 1.

Fig. 3 is an enlarged view of the connection between the fulcrum links and the main lever with the shifting rod connected thereto.

Like numerals refer to like parts throughout the several views.

Referring to the drawing, 10 indicates a pump cylinder, having a stuffing box 11, in which the pump plunger 12 is slidably mounted. An outlet pipe 13 transmits the pressure fluid from the cylinder to the hydraulic mechanism (not shown) whereby the load may be acted upon. The load, as previously described, is variable in its resistance to motion and hence the pressure of the hydraulic fluid should be varied and we accomplish this by changing the fulcrum point of the main lever 20 as will now be described.

The main lever 20 is pivoted to the plunger 12 as at 21 and is provided with an operating handle 22, this handle being grasped by the operator of the device who oscillates it to and fro thereby reciprocating the pump plunger 12 and this causes the pressure fluid to be transmitted through the outlet pipe 13. The lever 20 is offset 70 and provided with an opening as indicated at 23 and a sleeve 24 is rigidly mounted therein as is clearly shown in Fig. 3.

The sleeve 24 is closed at its upper end and a rod 25 slidably extends therethrough, the upper end of this rod being pivoted at 26 onto the short auxiliary lever 27 which, in turn, is pivoted onto the main lever 20 as indicated at 28.

The lower end of the rod 25 is threaded into a member 30, this member 30 snugly engaging the sleeve 24, see Fig. 3, and the lower end has an eye portion 31 fitting around the pivot bolt 32.

The pivot bolt 32 passes through the fulcrum links 33, these links being pivoted at their opposite ends to the bracket 35 as indicated at 34. 100 See Fig. 1.

A coiled spring, 36, see Fig. 3, surrounds the lower end of the rod 25 and pushes against the upper end of the member 30 thus causing the pivot bolt 32 to be shifted downwardly to the 105 dotted line position as shown in Fig. 1, whenever the auxiliary lever 27 is moved from its upright dead center position, such being shown in full lines in Figs. 1 and 2. Hence, whenever the lever 27 is shifted clockwise, see Fig. 1, the spring 36 110

immediately becomes operative and pushes the links 33, together with the fulcrum 32 of the main lever 20, downwardly and the auxiliary lever 27 also assumes the dotted line position shown in 5 Figs. 1 and 2.

From the above description, it will be seen that whenever the pressure of the hydraulic fluid materially changes that the fulcrum point may be shifted to correspond therewith by means of the 10 mechanism described and set forth. It is also within the purview of our invention to adjust the auxiliary handle 27 to a series of positions whereby the pivot pin fulcrum 32 will be correspondingly varied.

15 We claim:

In an operating device for a variable load, the combination of an oscillatable lever adapted to

be the prime mover, said lever having a handle at one end, a slot near the other end and offset laterally therebetween, a fulcrum link pivoted to a fixed pivot and extending adjacent said slot in said lever, pivotal means extending through the 80 said slot and the adjacent link, a sleeve extending alongside of the lever and through said offset portion whereby it is rigid therewith, slidble means mounted in said sleeve, means connecting one end of the slidble means to the pivotal means whereby the same may be moved along the said slot, means at the other end of the said slidble means whereby it may be reciprocated for the purpose desired and operating means connected 85 between the lever and the load.
